Primary Examiner—George G. Stellar

Attorney, Agent, or Firm—C. Clark Dougherty, Jr.

[57] **CLAIM**

The ornamental design for a boot installation and removal device, substantially as shown and described.

DESCRIPTION

FIG. 1 is a side elevational view of a boot installation and removal device showing our new design;

FIG. 2 is a top plan view thereof;

FIG. 3 is a bottom plan view thereof;

FIG. 4 is an end elevational view thereof; and

FIG. 5 is an elevational view of the other end thereof.
